US0D1024012S

(12) **United States Design Patent** (10) **Patent No.:** **US D1,024,012 S**
(45) **Date of Patent:** **** Apr. 23, 2024**

(54) **COMBINED WIRELESS EARPHONES AND CHARGING CASE**

(71) Applicant: **Yifeng Zhang**, Xinhua (CN)

(72) Inventor: **Haimei Xu**, Xinhua (CN)

(73) Assignee: **Yifeng Zhang**, Xinhua (CN)

(**) Term: **15 Years**

(21) Appl. No.: **29/841,672**

(22) Filed: **Jun. 8, 2022**

(30) **Foreign Application Priority Data**

Jan. 13, 2022 (CN) 202230021839.9

(57) **CLAIM**

The ornamental design for a combined wireless earphones and charging case, as shown and described.

DESCRIPTION

FIG. 1 is a perspective view of a charging case for the combined wireless earphones and charging case, shown separately for ease of illustration;

FIG. 2 is an opposite perspective view thereof;

FIG. 3 is a front elevational view thereof;

FIG. 4 is a back elevational view thereof;

FIG. 5 is a left side view thereof;

FIG. 6 is a right side elevational view thereof;

FIG. 7 is a top view thereof;

FIG. 8 is a bottom view thereof;

FIG. 9 is a perspective view of a wireless earphone of the combined wireless earphones and charging case shown separately for ease of illustration;

FIG. 10 is a perspective view thereof;

FIG. 11 is a front view thereof;

FIG. 12 is a back view thereof;

FIG. 13 is a left side view thereof;

FIG. 14 is a right side view thereof;

FIG. 15 is a top view thereof;

FIG. 16 is a bottom view thereof;

FIG. 17 is a perspective view of the charging case of the combined wireless earphones and charging case in an open configuration thereof; and,

FIG. 18 is a perspective view of a combined wireless earphones and charging case in an open configuration thereof.

The broken lines shown in the drawings depict portions of the combined wireless earphones and charging case that form no part of the claimed design.

1 Claim, 18 Drawing Sheets
